UNITED STATES PATENT OFFICE.

MICHAEL D. FITZGERALD, OF BLOOMINGTON, ILLINOIS, ASSIGNOR TO
MAGGIE R. FLAGG, OF SAME PLACE.

HEATING AND VENTILATING CARS.

SPECIFICATION forming part of Letters Patent No. 252,752, dated January 24, 1882.

Application filed November 7, 1881. (No model.)

To all whom it may concern:

Be it known that I, MICHAEL D. FITZGERALD, of Bloomington, in the county of McLean, and in the State of Illinois, have invented certain new and useful Improvements in Heating and Ventilating Cars; and I do hereby declare that the following is a full, clear, and exact description thereof, reference being had to the accompanying drawings, and to the letters of reference marked thereon, making a part of this specification.

My invention relates to certain new and useful improvements in the class of heaters and ventilators more especially designed for rail-road-cars; and it consists in novel features of construction and combination and arrangement of parts, all as will be hereinafter fully described, and specifically designated in the claims.

Referring to the accompanying drawings, Figure 1 represents a sectional elevation of my improved heater and ventilator on line w w , Fig. 3. Fig. 2 is a side elevation. Fig. 3 is a sectional elevation on line x x , Fig. 2. Fig. 4 is a horizontal section on line y y , Fig. 2. Fig. 5 is a horizontal section on line z z , Fig. 2; Fig. 6, a horizontal section on line w w , Fig. 3.

In the drawings, A represents a suitable heater or furnace; A', the ash-pit bottom; a a', the furnace and ash-pit doors, and a² the smoke stack or pipe.

B represents the base, extending in rear of the heater or furnace; and C, an outside casing, which entirely surrounds the top and sides of the heater or furnace, and attached in any suitable manner to the base B. The base B is provided with a closed bottom, and on one side with opening b, and also has connected to and communicating therewith, at its rear extended end; a ventilating-shaft, D, which extends up through the top or roof of a car, and is provided at its upper end with a ventilating cowl or hood, d, arranged to move or swing properly with the wind. The base B is also provided on one side with an air-chamber, b', which communicates with the space between outside casing, C, and heater or furnace; and said chamber b' is provided with an opening, b², controlled by a damper, b³, for admitting fresh

air to the space between casing C and heater, 50 and which can be accomplished through a window of the car by a pipe connecting the opening b² with the window. The fresh air, heated in its passage through the space between outside casing and heater or furnace, passes out 55 into the car through openings c in the top of said casing, controlled by a register, c'.

A register, c², arranged in the casing C, on the opposite side from opening b², (see dotted lines, Fig. 2,) admits of the better or purer 60 portions of the air in the car being passed between casing and heater or furnace and out through the top of the casing into the car again, so that said air can be heated over and over again when desired. 65

A pipe, E, provided with a valve or damper, e, connects the space between the casing and heater or furnace with the ventilating-shaft D.

The ventilating-shaft is provided with slide-dampers d' near the roof of car, and the 70 smoke stack or pipe passes up through the upper portion of the ventilating-shaft, for purposes to be hereinafter described.

The fresh air is admitted through opening b², as before described, and the damper b³ regulates the amount of fresh air to be admitted to the space between casing and heater or furnace, and may shut off entirely the outer or fresh air if the car is little occupied. In the latter case the register c² of the casing is 80 opened, and the air in the car is admitted into the space between casing and heater or furnace, and warmed and passed into the car through the openings in top of casing, so that the air can be warmed over and over again, or 85 partially so, as hereinafter described.

If the car is crowded and nothing but outside fresh air is to be heated, the register c² is closed and damper b³ opened; so as to admit the fresh air. The air in the ventilating-shaft 90 being rarefied by the heat from the smoke-pipe passing up through the upper portion of said shaft, passes out into the open air, together with the products of combustion from the smoke-pipe, and in consequence thereof the foul air 95 from below in the foul-air chamber B' rushes into the ventilating-shaft to take its place, thereby taking the fouler and heavier portions

of the air from the bottom of the car—the carbonic-acid gas, &c.—through opening b into chamber B' , and thence into the ventilating-shaft into the open air.

5 If it is desirable to warm over a portion of the air in the car, the register c^2 can also be opened, when the lighter and better portions of the air in the car will be taken into the casing and, with the outside air, be warmed anew, 10 and both pass through the top of casing into the car.

If the air in the car gets too warm, the register in top of casing can be closed entirely, and thus the heated air shut off from the car, 15 and by opening valve or damper e be discharged through pipe E into the ventilating-shaft.

If desired, the sliding dampers d' can be opened, so that the air in the car will pass directly into the upper portion of ventilating- 20 shaft and thence into the open air.

Having thus fully described my invention, what I claim as new, and desire to secure by Letters Patent, is—

1. In a heater and ventilator for cars, the 25 combination of the base-chamber B' , having opening b , its rear extended portion having ventilating-shaft D communicating therewith, heater or furnace A , having smoke-pipe a^2 extending through upper portion of ventilating- 30 shaft, casing C , surrounding top and sides of heater or furnace and having openings c through the top thereof, and register c' and air-chamber b' , located in base B , and communicating with space between casing and heater 35 or furnace, and provided with opening b^2 and damper b^3 , substantially in the manner, as and for the purpose herein shown and described.

2. In a heater and ventilator for cars, the combination of base-chamber B' , having opening b and ventilating-shaft D communicating therewith, heater or furnace A , having smoke-pipe extending through upper portion of ventilating-shaft, surrounding casing C , having registers c' c^2 , connecting-pipe E , provided with valve or damper e , and air-chamber b' , having opening b^2 and damper b^3 , said pipe E and air-chamber b' communicating with the space between casing C and heater or furnace, substantially in the manner as and for the purpose herein shown and described. 40 50

3. In a heater and ventilator for cars, the combination of base-chamber B' , having opening b , ventilating-shaft D communicating therewith, and having damper or dampers d' near its upper end, and movable cowl or hood d , 55 heater or furnace A , having smoke-pipe extending through upper portion of shaft D , outside casing C , having registers c' c^2 , pipe E , having valve or damper e , and air-chamber b' , having opening b^2 and damper b^3 , said pipe E and air-chamber b' communicating with space 60 between casing and heater or furnace, the several parts constructed and arranged relatively to each other, substantially as herein shown and described. 65

In testimony that I claim the foregoing I have hereunto set my hand this 12th day of May, 1881.

MICHAEL D. FITZGERALD.
